UNITED STATES PATENT OFFICE.

AMOS RANK, OF SALEM, OHIO.

DESIGN FOR GRAVE-GUARDS.

Specification forming part of Design No. 7,781, dated September 29, 1874; application filed August 28, 1874.
[Term of Patent 14 years.]

CASE D.

To all whom it may concern:

Be it known that I, AMOS RANK, of Salem, in the county of Columbiana and State of Ohio, have invented a Design for Grave-Guards, of which the following is a specification:

The nature of my invention is fully represented in the accompanying drawings, to which reference is here made.

The guard, as concerns its upper and under surfaces, is nearly or quite flat, with its circumferential surface flaring or sloping outward and downward, as clearly shown in the drawings. The end portions A of the guard are of rectangular shape. The central portion B is of less diameter, taken transversely, than the end portions just set forth. The lateral surfaces of this central portion are straight and parallel with each other, and are joined to the adjacent lateral surfaces of the end portions A by curves *a*; or, when desired, by straight surfaces running at the requisite an-

gles from the lateral surfaces of A to those of B. Formed centrally within the guard is an open space, C, the contour of which may correspond, more or less, with that of the external circumference of the guard.

The end portions of the guard may be, when desired, formed with upwardly-projecting pyramidal parts D; but the omission of these will in no way affect the identity of my design.

What I claim as my invention is—

The design for a grave-guard in which the end portions are of rectangular form, and the central portion with straight parallel sides, connecting with the end portions by curves or short straight surfaces, substantially in the manner herein described and shown.

AMOS RANK.
